UNITED STATES PATENT OFFICE.

JOHN A. WATSON, OF CINCINNATI, OHIO, ASSIGNOR OF ONE-HALF TO JOSEPH H. SHEICK, OF CINCINNATI, OHIO.

CHIMNEY.

Application filed May 24, 1922. Serial No. 563,337.

To all whom it may concern:

Be it known that I, JOHN A. WATSON, a citizen of the United States, residing at Cincinnati, in the county of Hamilton and 5 State of Ohio, have invented certain new and useful Improvements in Chimneys, of which the following is a specification, reference being had to the accompanying drawings.

10 This invention relates to chimneys and more particularly to chimneys for heating plants.

An object of the invention is to provide a chimney of this character provided with 15 means for insulating the heat within the chimney so as to eliminate the possibility of fire in the building due to the radiation of heat from the chimney.

Another object of the invention is to provide a chimney of this character composed 20 of a plurality of sections arranged to telescopically engage each other.

A further object of the invention is to provide a chimney of this character composed 25 of a plurality of sections, each section including an inner and outer wall, with heat insulating material disposed between said walls, the end portions of each section being adapted to telescope the end portions 30 of the adjacent sections.

With these and other objects in view, the invention consists in the improved construction and arrangement of parts to be hereinafter more particularly described, fully 35 claimed and illustrated in the accompanying drawings, in which:—

Figure 1 is a longitudinal sectional view 40 of a chimney constructed in accordance with an embodiment of the invention, the sections of the chimney being shown disconnected;

Figure 2 is a longitudinal sectional view showing the sections connected; and

Figure 3 is a top plan view of the intermediate section.

Referring to the drawings, 5 designates the lower base section, 6 the top section or chimney shaft, and 7 the intermediate section. It is of course obvious that any number 50 of the intermediate sections may be provided to construct the chimney the length desired.

The section 5 consists of an outer tubular wall 8 constructed of metal, the wall tapering from its end 9 to its end 10, said end 10 having an inwardly projecting flange 11 adapted to reinforce said member.

The end 9 is adapted to be imbedded in a concrete base A. It is of course obvious that the section 5 may be made any length desired. In order to insulate the heat from the portions of the building adjacent the wall 8, an inner wall 12 is provided, said wall being tubular and tapering from its end portion 13 to its end portion 14, the end portion 13 being embedded in the concrete base A, while the extremity of the end portion 14 is formed into a flange. With this arrangement the diameter of the inner tubular wall 12 is smaller than the diameter of the outer tubular wall 8, so that the wall 12 is disposed in spaced relation to the wall 8. Disposed inwardly of the end portions 10 and 14 of the walls 8 and 12 is 55 a partition 15 which serves to hold the walls 8 and 12 in spaced relation to each other and to coat with said walls to provide a compartment 16 adapted to receive powdered asbestos, the asbestos serving to insulate the heat within the tubular member 12. The portions of the end portions 14 and 10 of the walls 8 and 12 projecting beyond the partition 15 are used as connecting means for 60 connecting the lower end section to the adjacent intermediate section. To facilitate cleaning, the end section is provided with a soot pan 17 which may be readily removed.

In the construction of the chimney any number of intermediate sections may be provided, the intermediate sections comprising an outer tubular metal wall 18 having a flange formed exteriorly of the end portion 19 of the wall and a flange formed interiorly of the end portion 20 of the wall. Disposed inwardly of the wall 18 is an inner metallic tubular wall 21, the end portion 22 of said wall having a flange disposed exteriorly thereof, while the end portion 23 has a flange disposed interiorly thereof. A partition 24 is disposed inwardly 65 of the end portions 20 and 23 and 19 and 22, said partitions coating with the walls 18 and 21 to provide a compartment 24 adapted to receive powdered asbestos so as to 70

insulate the heat within the tubular wall 21. The intermediate section that is adapted for engagement with the end section is provided with registering openings 25 in the 5 walls 21 and 18 through which a flue 26 extends, said flue extending through the compartment 24^a and is adapted to receive the end of a pipe leading from the heating plant. The end portion 19 of the tubular 10 wall 18 has a collar 27 secured thereto, said collar terminating at the lower partition 24 and is also disposed between the walls 18 and 21. A similar collar 28 is secured to the inner face of the tubular wall 21. The 15 collar 28 coacts with the end portion 22 to provide a compartment for the reception of the end portion 14 of the section 5, while the collar 27 coacts with the end portion 19 to provide a collar for the reception 20 of the end portion 10 of the section 5. In this way a pipe joint is provided which not only prevents leakage of smoke and gases, but at the same time the heat is prevented from reaching the outer tubular 25 walls of the sections. It will also be noted that in the engagement of the sections 7 with the sections 5 that the flanges on the ends of said sections are so disposed that they do not conflict or interfere with 30 each other and at the same time properly reinforce the ends of the sections. Any number of the sections 7 may be provided, and it is not necessary that collars 27 and 28 be provided for each of the intermediate 35 sections, but only the section adjacent the end section 5.

The top or chimney shaft section, similar to the sections 5 and 7, comprises an outer tubular wall 29 and an inner tubular 40 wall 30 which are spaced from each other, the end portion 31 of the wall 29 having a flange disposed exteriorly thereof, while the end portion 32 of the wall 30 has a flange disposed exteriorly thereof and between the 45 walls 29 and 30. A partition 33 is disposed between the walls 29 and 30 while a top member 34 is secured to the upper ends of the walls 29 and 30, the top 34 and partition 33 coacting with said walls to provide 50 a compartment 35 for the reception of powdered asbestos.

In this construction it is of course obvious that a chimney cap 36 may be secured to the top 35 and outer wall 29, and in the 55 construction of this cap solder may be used as the asbestos prevents the radiation of heat and thus eliminates melting of any solder used in the formation of the cap. The end portion 31 of the section 6 is adapted to 60 telescope the end portion 20 of the section 7 exteriorly of the end portion 20, while the end portion 32 of the section 6 is arranged to telescope the end portion 23 of the section 7 likewise exteriorly of said end portion. 65 Telescoping movement of said ends is lim-

ited by contact of the flanges of said sections with the adjacent partitions between the walls.

In the construction of the end section 5, it is preferred that the inner and outer walls 70 be constructed of galvanized iron, while the inner walls of the remaining section are constructed of copper and the outer walls of galvanized iron, the copper serving to retain 75 the heat within the chimney.

It will also be noted that the partitions of each end portion of the sections are disposed inwardly of the sections a distance corresponding to the length of the end portions projecting beyond the partitions so that 80 each partition serves as a stop for the telescoping ends of the adjacent section.

From the foregoing it will be readily seen that this invention provides a novel form of chimney which is not only capable for use in small houses, but also in factories, as it can be made any size or length desired. The temperature of the heat within the chimney does not have to be watched or regulated, as there is no danger of fire in view of the protection afforded by the inner walls and the asbestos compartments. Furthermore, the asbestos within the compartments serves as means for holding the sections in engagement with each other, in view of the weight 90 thereof. All of these features are possessed by a chimney composed of sections capable of being readily assembled.

What is claimed is:—

1. A chimney comprising a plurality of 100 sections, each section embodying an inner and outer tubular wall, spacing means disposed between said walls, said means coacting with the walls to provide a compartment for the reception of heat insulating means, the end portions of said sections telescopically engaging the end portions of the adjacent sections.

2. A chimney comprising a plurality of 110 sections, each section embodying an outer tubular wall and an inner tubular wall, one end portion of each of the end sections and both end portions of the intermediate sections having partitions disposed inwardly 115 thereof between the inner and outer walls, said partitions coacting with the inner and outer walls to provide compartments for the reception of heat insulating means, that portion of the end portions of said sections projecting outwardly from the partitions telescopically engaging the corresponding end portions of the adjacent sections, said partitions serving as means to limit telescopic movement of said sections.

3. A chimney comprising a plurality of 125 sections, each section embodying an inner and outer tubular wall, partitions disposed inwardly of the end portions of said walls for spacing the inner and outer walls from each other, said partitions coacting with 130

said walls to provide compartments arranged to receive asbestos, that portion of the end portions of each section projecting beyond the partitions telescopically engaging the 5 end portions of the corresponding tubular walls of the adjacent sections, the intermediate section of the chimney adjacent the lower end section having collars disposed in-

wardly of the lower end portions thereof, said collars coacting with the adjacent end 10 portion of the intermediate section for the reception of the end portions of the lower end section.

In testimony whereof I hereunto affix my signature.

JOHN A. WATSON.
